UNITED STATES PATENT OFFICE.

SAMUEL SKERPAN, OF ANSONIA, CONNECTICUT.

CANDLESTICK.

1,315,872.

Specification of Letters Patent. Patented Sept. 9, 1919.

Application filed May 5, 1919. Serial No. 294,967.

To all whom it may concern:

Be it known that I, SAMUEL SKERPAN, a citizen of Ukraine, residing at Ansonia, in the county of New Haven and State of Connecticut, have invented certain new and useful Improvements in Candlesticks, of which the following is a specification.

The primary object of the present invention is to provide an improved form of candle stick, in which the clamping blocks for engaging the candle are adjustably mounted upon the base member whereby candles of different diameters may be readily accommodated, and in which the clamping bars are so adjustable as to have candles of different diameters centrally located of the supporting base.

With the above and other objects in view, the invention consists in the novel form, combination and arrangement of parts hereinafter more fully described, and shown in the accompanying drawing, in which like reference characters indicate corresponding parts through the several views.

25 In the drawing,

Figure 1 is a side elevational view of a candle stick which is constructed in accordance with the present invention, the same being partly broken away and shown in section, better to illustrate the adjusting means for the movable clamping blocks,

Fig. 2 is a top plan view partly broken away and partly in section,

Fig. 3 is a side elevational view of a portion of the device,

Fig. 4 is a vertical sectional view taken on line IV—IV of Fig. 1 showing the screw operated candle clamping block, and

Fig. 5 is a vertical sectional view on line V—V of Fig. 1 showing the adjustably mounted candle clamping block.

Referring more in detail to the accompanying drawing, the reference numeral 6 denotes a candle stick for a supporting base 7 of any approved form of design, preferably as shown in Figs. 1 and 2 while the upper end thereof is peculiarly constructed to receive a pair of adjustably mounted clamping blocks 8 and 9. The upper end of the stick 6 is provided with upstanding parallel guide bars 10 carrying inwardly directed flanges 11 which form a recess 12 at the upper end of the stick 6. A pair of end plates 13 and 14 extend between the guide bars 10 and constitute end bearings for a screw 15 and are retained in position by fastening screws 13', the end 16 of the screw 15 being revolvably mounted in the end plate 13 against longitudinal movement while the other end thereof freely extends through the plate 14 and is provided with an operating handle 17 upon the outwardly projecting end thereof. As shown in Figs. 1 and 2, the end of the screw 15 adjacent the plate 13 is free of threads and has a plain cylindrical surface 18 as is illustrated.

The clamping blocks 8 and 9 have their lower ends positioned in the recess 12 of the stick 6, the clamping block 8 having a centrally depending lug bifurcated to provide a pair of legs 19 that are adapted to straddle the smooth portion 18 of the bolt 15 while depending teeth 20 are carried laterally thereof and are adapted for selective engagement in corresponding openings 21 in the upper face of the flanges 11, as is clearly illustrated in Figs. 2 and 5. As shown in Fig. 4, the lower end of the clamping block 9 is T-shaped as at 22 to provide laterally projecting sides positioned beneath the overhanging flanges 11, there being provided a threaded opening 23 in the T-shaped end 22 of the clamping block 9 for engagement with the threaded portion 15 of the bolt as more clearly illustrated in Fig. 1.

In the use of the device, a candle indicated by the reference character A is centrally mounted upon the upper flanges 11 and a guide block 8 lowered into the recess 12 of the stick head with the forked end 19 straddling the smooth portion 18 of the screw while the teeth 20 of the block 8 are received in adjacent sockets 21 in said flanges. By manipulating the screw 15 through the medium of the handle 17, the block 9 is moved laterally of the stick head through the opening 12 until the same properly engages the lower end of the candle 8 to securely hold the same in a rigid condition. By reversing the movement of the screw, the block is moved in a direction away from the candle A and the candle may be removed therefrom. By this arrangement of holding the clamping block immovable, candles of different diameters may be readily accommodated to a single stick of standard size and the commercial value thereof will thereby be increased.

What I claim as new is:—

1. A candle stick comprising a supporting base, a pair of spaced parallel guide bars formed on the upper end thereof, the upper

faces of said bars having corresponding sockets formed therein, a clamping block having its lower end received between said bars, teeth carried by said block adapted to be received in the sockets in said bars, holding said block in fixed position, a second clamping block freely slideable between said bars, said second block having a threaded opening therein, and a threaded bolt associated with said bars and blocks adapted to move said second block toward and away from the first block to accommodate candles of different sizes.

2. A candle stick comprising a supporting base, a pair of spaced parallel guide bars formed on the upper end thereof, inwardly directed flanges carried by said bars, said flanges having corresponding sockets formed therein, a clamping block having a forked

lower end loosely received between said guide bars, depending lugs carried by said block for seating in said sockets for holding said block in adjusted position, a second clamping block having an inverted T-shaped lower end received between said guide bars, 25 the lower end of the second block having a threaded opening therein registering with the space between the fork of the first block, and a threaded bolt carried by the supporting base associated with the threaded opening in the second named clamping block, and having a plain portion passing through the fork of the first named block, whereby the second named block is adapted to be shifted upon movement of the screw. 30 35

In testimony whereof I affix my signature.

SAMUEL SKERPAN.
